UNITED STATES PATENT OFFICE.

JAMES T. R. GREEN, OF DES MOINES, IOWA.

DESIGN FOR A BRACE FOR EVENERS AND EQUALIZERS FOR PLOWS OR THE LIKE.

SPECIFICATION forming part of Design No. 34,076, dated February 12, 1901.

Application filed January 11, 1901. Serial No. 42,933. Term of patent 14 years.

To all whom it may concern:

Be it known that I, JAMES T. R. GREEN, a citizen of the United States of America, and a resident of Des Moines, Polk county, Iowa, have invented and produced a new and original Design for a Brace for Eveners and Equalizers for Plows or the Like, of which the following is a specification.

The object of this invention is to provide a new and original design for a brace for eveners.

My invention consists of the design herein-after set forth, pointed out in my claim, and illustrated by the accompanying drawings, in which—

Figure 1 is a plan of the brace embodying my design. Fig. 2 is an edge view of the brace embodying my design. Fig. 3 is a central longitudinal section of the brace embodying my design.

In the design, as illustrated, the numeral 10 designates the body portion straight, relatively broad and thin, of uniform width, and with a rounded end portion 11 and convex edge portions 12 13. An arm 14 extends at an angle from one end portion of the body 10 and has convex edges 15 16 and a rounded end portion 17. The arm 14 is offset relative

to the body 10 or, in other words, is in a plane parallel with the plane of the body and is connected thereto by an inclined portion 10^a of the body. An elongated aperture or slot 18, with concaved end portions, is formed in one end portion of the body 10, adjacent the rounded end 11 thereof. The slot 18 is formed midway of the convex edges 12 13 of the body

10. An elongated aperture or slot 19, with concaved ends, is formed in the arm 14 and is located midway of the convex edges 15 16 of said arm and parallel therewith. Both of the broad faces of the body portion 10 and inclined portion 10^a are concaved or hollowed out to form panels 20 21, thus providing a thin relatively broad central portion of the body with concaved faces.

I claim as my invention—

The design for a brace for eveners and equalizers for plows and the like, substantially as herein shown and described.

Signed by me at Des Moines, Iowa, this 7th day of January, 1901.

JAMES T. R. GREEN.
